Patented Sept. 21, 1920.

UNITED STATES PATENT OFFICE.

JOHN A. WIENER, OF ROTHSCHILD, WISCONSIN.

REGULATOR.

1,353,298.

Specification of Letters Patent. Patented Sept. 21, 1920.

Application filed March 27, 1920. Serial No. 369,386.

To whom it may concern:

Be it known that I, JOHN A. WIENER, a citizen of the United States, residing at Rothschild, county of Marathon, State of Wisconsin, have invented certain new and useful Improvements in Regulators, of which the following is a specification.

This invention relates to improvements in regulators.

10 In the accompanying drawing I have shown my improvements as embodied by me in a temperature regulator, the machine controlled or driven by the second motor not being illustrated as my present improvements do not relate to such features.

The main objects of this invention are:

First, to provide an improved regulator by means of which temperatures, speeds or pressures may be very accurately controlled.

20 Second, to provide an improved regulator means having these advantages which is entirely automatic.

Third, to provide an improved control apparatus which may be adjusted to the temperature desired and the temperature very evenly maintained at the point to which the apparatus is adjusted.

Further objects, and objects relating to structural details, will definitely appear 30 from the detailed description to follow.

I accomplish the objects of my invention by the devices and means described in the following specification. The invention is clearly defined and pointed out in the claims.

35 A structure which is a preferred embodiment of my invention is clearly illustrated in the accompanying drawing forming a part of this specification, in which:

The figure is a view mainly in diagrammatical form of a control apparatus embodying the features of my invention.

Referring to the drawing, 1 represents a governor valve driven from the motor 2, the motor shaft 3 being connected to the 45 governor by the worm 4.

A second motor 5 is shown conventionally and this second motor may drive a stoker or blower or other machine used in connection with a heating system or steam plant.

50 The device illustrated is especially designed by me for regulating the temperatures of steam in the driers of a paper making machine and the numeral 6 represents a thermometer bulb adapted to be inserted into the drier. This bulb is connected by a flexible tube 7 with a recording thermometer

having a chart 8 and a pen carrying arm 9 pivoted at 10, the pivot being provided with an arm 13 connected by the link 14 to the recording thermostatic mechanism which is 60 not here shown as such mechanism forms no part of this invention.

An arm 15 is adjustably secured to the pivot 10 of the pen carrying arm. This arm 15 is provided with a pin 15' engaging a 65 slot 16' in the arm 16 projecting upwardly from the balance beam 17 which is pivoted at 18. With this connection, when the arm 15 is swung through the thermostatic means, the pen carrying arm is moved relative to 70 the chart. The arm 15 also swings or moves to tilt the balance beam 17 through the pin and slot connection described. This balance beam carries receptacles 19 containing mercury or other suitable liquid adapted to 75 contact with the contact pins 20. These contact pins are of graduated length, the length being such that when the balance beam is on center the pins are partially submerged and partially above the mercury. These contact pins are connected by the wires 21 to a series of resistance units 22 in the motor circuits, so that as the contact pins are submerged in or withdrawn from the mercury, the resistance units are cut into or out of the motor 80 circuit, thus increasing or diminishing the speed of the motor. In the structure illustrated, the apparatus is designed to control two motors and the speeding up or reducing of the motors depends on whether 85 the resistance is cut into the field or on the rotor of the motor, so that by connecting one set of resistance units to the rotor of one motor and the other set of resistance units to the field, both motors may be speeded up or their speed reduced simultaneously. 95

As illustrated in the accompanying drawing, the contact points are about one-half submerged, a coating of oil being provided over the surface of the mercury to prevent 100 sparking as the contact points are withdrawn or submerged. With the parts in this position the motor would be running at one-half speed, the speed increased or decreased according to the actuation of the beam through the thermostatic control means. 105

Where it is only desired to control the temperature, a single device or unit is all that is required. The second unit, however, 110 will be found to be of advantage as it may be used to control the fan or blower motor

2
or the stoker, as may be desired. The governor valve may be used to control the delivery of steam for various purposes as may be desired, as to an engine, automatically regulating the speed thereof. Of course, either of the motors may be adapted to any desired end.

I have not attempted to illustrate or describe the various adaptations of my improvements as I believe the disclosure made will enable those skilled in the art to which my invention relates to embody or adapt the same as may be desired.

Having thus described my invention, what I claim as new and desire to secure by Letters Patent, is:

1. In an apparatus of the class described, the combination of a pair of motors, control means for said motors each comprising a series of resistance units, groups of contact points of graduated length connected to said series of resistance units, a recording thermometer comprising a pen arm pivot, an arm adjustably attached to the pivot, a beam having a central arm operatively associated with said arm on said pen arm pivot, and receptacles carried by said beam and containing mercury coacting with the said groups of contact points, for the purpose specified.

2. In an apparatus of the class described, the combination of a pair of motors, a balance beam, control means for said motors each comprising a series of resistance units, groups of contact points of graduated length connected to said series of resistance units, receptacles carried by said beam and containing mercury coacting with the said groups of contact points and means for controlling said balance beam.

3. In an apparatus of the class described, the combination of a motor, a control means for said motor comprising a series of resistance units, a group of contact points of graduated length connected to said series of resistance units, a recording thermometer comprising a pen arm pivot, an arm adjustably attached to the pivot, a pivoted beam operatively associated with said arm on said pen arm pivot, and a receptacle carried by said beam and containing mercury coacting with the said group of contact points, for the purpose specified.

4. In an apparatus of the class described,

the combination of a pair of motors, a beam, a thermostatic means for controlling the said beam, control means for said motors each comprising a series of resistance units, groups of contact pins of graduated length connected to said resistance units, and receptacles carried by said beam and containing a liquid coacting with said contact pins, for the purpose specified.

5. In an apparatus of the class described, the combination of a motor, a beam, a thermostatic means for controlling the said beam, a control means for said motor comprising a series of resistance units, a group of contact pins of graduated length connected to said resistance units, and a receptacle carried by said beam and containing a liquid coacting with said contact pins, for the purpose specified.

6. In an apparatus of the class described, the combination of a motor, a control means for said motor comprising a series of resistance units, a series of contact points connected to said series of resistance units, a receptacle containing mercury coacting with said contact pins to control said resistance units, and a thermostatically actuated means for raising and lowering said receptacle, for the purpose specified.

7. The combination in a temperature regulating apparatus including a motor, of a control means for said motor comprising a series of resistance units, a series of contact points connected to said series of resistance units, a receptacle containing a fluid coacting with said contact pins to control said resistance units, and thermostatically controlled means for regulating the submersion of said contact pins in said liquid.

8. The combination in a temperature regulating apparatus including a motor, of means for controlling the current to the motor comprising a series of contact pins, a receptacle containing a liquid coacting with said contact pins, and thermostatically controlled means for regulating the submersion of said contact pins in said liquid.

In witness whereof I have hereunto set my hand and seal in the presence of two witnesses.

JOHN A. WIENEK. [L.S.]
